FRANCIS M. WEST, OF YONKERS, NEW YORK, ASSIGNOR TO ARTHUR B. WARING, OF YONKERS, NEW YORK.

STENCIL.

1,134,571.

Specification of Letters Patent.

Patented Apr. 6, 1915.

Application filed July 12, 1912. Serial No. 709,055.

To all whom it may concern:

Be it known that I, FRANCIS M. WEST, a citizen of the United States, residing at Yonkers, New York, have invented the following new and useful Improvements in Stencils.

My invention relates to stencils and more particularly to hollow shell-form stencils for use in decorating hat bodies.

10 One object of my invention is to provide an improved reticulated plate or hollow shell stencil, by electro-depositing metal upon a conducting surface having the general shape of the hat body and previously 15 prepared according to the form or outline of the decorative design to be applied.

Other objects and advantages of my invention will be set forth hereinafter, and in order that my invention may be thoroughly understood, I will now proceed to 20 describe the same in the following specification and then point out the novel features thereof in appended claims.

In the drawing forming part hereof, Fig. 25 ure 1 represents a partly sectional view of the bed and backing for the conducting surface; Fig. 2 a detail of the wire conductor in section; Fig. 3 represents an elevation detail, showing a design worked upon 30 the conducting surface; Fig. 4 is a section of the stencil on removal, in slightly enlarged scale; Fig. 5 the same after coating; and Fig. 6 represents the completed stencil.

In carrying out the invention I make a 35 suitable support or backing for the conducting surface, as shown at 1, giving to it approximately the external shape of the hat-body or other article to be decorated; that is to say, the shape of a cone with a rounded 40 top like that of a hat-body before it has been shaped with crown and brim portion. Such cone-shaped support may be made hollow and of plaster Paris and is also provided with a hook 2 or other form of attachment means by which it can be suspended 45 in the electrolytic bath from the terminal bar thereof. A film of wax, 3, is applied to the outer surface of the cone-shaped backing 1, as for example by dipping it one or more times in melted wax, which will bring the overall dimensions of the wax-covered support to the size desired, and which should be about the same as, or a little larger than, that of the hat body 50 55 which the stencil is to be used to decorate.

At the same time as applying the wax covering, a circular wire 4 is placed against the lower and outer margin of the support and embedded in the wax so as to become thereby attached to the plaster backing sufficiently to support the latter. The hook 2 60 may be formed of one end or the middle of this wire, or attached to it in any suitable way. After the wire has been thus fastened to the support, graphite is applied to the 65 wax over the whole surface thereof down to the location of the wire and at one or more points a notch is formed in the rim of wax covering the wire, as shown at 5 in Fig. 1, which is for the purpose of exposing the 70 wire at such point or points so that it may thereby have suitable electrical contact with the graphite surface, thus putting the same in electrical connection with the suspension hook 2. The design for the stencil is then worked 75 on the conducting graphite surface of the wax, as illustrated by Fig. 3. This may be done by scraping or removing the graphite from the portions desired to be reproduced as 80 openings in the stencil as indicated at 6, or it can be done by applying the graphite only to those portions desired to be reproduced as the solid or imperforate part of the stencil; in either case producing on the bed surface a design made out of conducting 85 material and conforming to the design desired for the stencil. The backing or support with the design worked thereon is then gradually introduced into the electrolytic 90 bath, by immersing it first at the place or places where connection has been made with the wire, so as to build up substantial metallic bonds at these points between the wire and the adjacent, decorated, graphite surface. The rest of the wax covering the wire 95 is then removed so as to uncover the whole or the greater part of it, and the electro-depositing process continued until metal has been deposited all over the graphite 100 conducting surface as well as the surface of the wire, to a sufficient thickness to enable the resulting reticulate shell to be removed and handled without collapse. Such removal can be easily accomplished by immersion in hot water which softens the wax 105 and releases the metal. The wire 4 will be found more or less enveloped by the deposited metal film and in any event so securely attached to it as to serve the purpose 110 of a marginal flange or reinforcement like

an ordinary wire-bead flange which it closely resembles. The metal shell is then cleaned and coated with a covering to smooth and fill in its rough surfaces and give it further stiffness. This coating may be applied by dipping the whole shell in molten lead or other low-fusing metal, which on removal will form a thin coating on the inside as well as the outside without however appreciably affecting or filling in the stencil openings which will remain the same size and with rather sharp edges by reason of the tendency of fluid metal to collect in mound form on the intervening flat surfaces. It is preferred however to coat only one side of the shell which is done by flowing solder thereon. Fig. 5 shows a cross-section of the stencil as thus coated, 7 being the solid parts of the original stencil shell between the openings 6, and 8 being the solder coating on the intervening flat parts, mounded over as described. The design originally worked on the graphite surface, and reproduced in the stencil 9 shown in Fig. 6, can thereupon be transferred to the hat body in an obvious way and will form thereon a design which is peripherally continuous and unmarred by any interruptions in its uniformity of effect. It will be understood that the hat body, after receiv-

ing such stenciled design, is thereafter suitably worked and finished, but such subsequent treatment forms no part of my invention and description thereof is therefore omitted. It will be understood, moreover, 35 that the particular design given to the stencil is unimportant to the method of its formation, provided it is such as will form a continuous conductor for the current, and it will be observed that the effect thereof will 40 be that of a hand-made design following the effect produced by hand on the waxed surface.

I claim:

A stencil of the kind described comprising a hollow thin electro-deposited metal shell having reticulations formed therein to represent an ornamental design, a reinforcing wire embedded in the shell near its edge and a reinforcing flowed metal coating on 50 one side having the form of mounds between said reticulations, whereby the edges thereof are relatively sharp.

In testimony whereof, I have signed this specification in the presence of two wit- 55 nesses.

FRANCIS M. WEST.
